UNITED STATES PATENT OFFICE.

FRANK M. A'HEARN, OF GREENVILLE, PENNSYLVANIA.

FRAME SUPPORT.

1,422,164.

Specification of Letters Patent. Patented July 11, 1922.

Application filed February 21, 1922. Serial No. 538,215.

To all whom it may concern:

Be it known that I, FRANK M. A'HEARN, a citizen of the United States, residing at Greenville, in the county of Mercer and State 5 of Pennsylvania, have invented new and useful Improvements in Frame Supports, of which the following is a specification.

Locomotive frames are usually carried by the axle bearings through saddles which 10 straddle the frame support and rest on the boxes of the bearings and springs mounted on the saddles and linked to the frame, the support of the frame being communicated to the axles through these springs and 15 saddles.

When the spring becomes broken or weakened in order to support the frame and to properly adjust the load on the frame it is desirable that the frame be carried at about 20 the same relation to the bearing box that it is normally carried by the spring. Again it sometimes happens that one of the bearings of a locomotive becomes heated, or otherwise impaired and it is desirable to 25 relieve this bearing of the weight.

With the present invention it is desirable to carry the weight of the frame independently of the spring and to relieve the bearing of the weight upon it.

30 The invention is illustrated in the accompanying drawings as follows:—

Fig. 1 is an end view, the saddle being partly in section on the line 1—1 in Fig. 2.

Fig. 2 is a side view of Fig. 1, the left 35 half of the saddle and bearing being shown in section taken on the line 2—2 in Fig. 1.

Fig. 3 is a view similar to Fig. 2 but with a variation in the application of the support.

Fig. 4 is a side elevation of the support- 40 ing block.

Fig. 5 a side elevation of an alternative construction of the saddle.

1 marks the axle, 2 the drive wheel, 3 a bearing box resting on the axle, 4 the 45 frame, 5 the guide surfaces on the frame engaging the bearing box, 6 a supporting spring, 7 links suspending the frame from the spring, and 8 a saddle which straddles the frame, the legs resting on the bearing 50 box and supporting the springs. These parts are of usual construction except that the saddle has the perforations 9 and 10 through the side walls, one above the frame and one below.

55 In the normal operation of the locomotive

the yielding of the spring permits the bearing to move vertically with relation to the frame there being sufficient play in the saddle to permit of this movement. When it is desired to relieve the bearing of the 60 weight of the locomotive a bearing block 11 is placed in the saddle above the frame. This block is provided with a perforation 12 and a pin 13 is passed through the perforations 9 and the perforation 12, thus se- 65 curing the block in place on the frame and lifting the saddle from the bearing thus relieving it of weight. In order to adjust the supporting block to lift the saddle to the desired degree the supporting block has 70 the perforation 12 arranged at varying dis- 75 tances from its sides so that by turning the block varying amounts of supporting metal can be interposed between the pin 13 and the frame.

When the spring becomes weakened or broken the bearing block may be placed below the frame and the pin 13 passed through the perforations 10 and through the perforation 12 in the supporting block. Here 80 again the varying dimensions of the block permit of the block being so adjusted as to properly support the frame.

The saddle may be provided with a slot 14 in lieu of the two perforations 9 and 85 10 and will support the pin in as much as the pressure in each instance is away from the frame.

What I claim as new is:—

1. In a frame support, the combination of 90 a frame; a saddle straddling the frame; a bearing box supporting the saddle, said saddle having perforated sides; a supporting block arranged between the legs of the saddle and operating against the frame and 95 forming a support, said block having a perforation therethrough; and a pin extending through the perforations in the saddle and the block.

2. In a frame support, the combination 100 of a frame; a saddle straddling the frame; a bearing box supporting the saddle, said saddle having perforated sides; a supporting block arranged between the legs of the saddle and operating against the frame and 105 forming a support, said block having varying dimensions to adjust its supporting relation to the frame and a perforation therethrough; and a pin extending through the perforations in the saddle and the block. 110

3. In a frame support, the combination of a frame; a saddle straddling the frame; a bearing box supporting the saddle, said saddle having perforated sides; a supporting block arranged between the legs of the saddle and operating against the frame and forming a support, said block having a perforation therethrough and said block having its sides varying in distance from the 10 perforation therethrough; and a pin extending through the perforations in the saddle and the block.

4. In a frame support, the combination of a frame; a saddle straddling the frame, the 15 sides of said saddle being perforated; a bearing box supporting the saddle; a supporting block under the frame, said block having a perforation; and a pin extending

through the perforations in the saddle and the block.

5. In a frame support, the combination of a frame; a saddle straddling the frame, the sides of said saddle being perforated; a bearing box supporting the saddle; a supporting block under the frame, said block 25 having a perforation, and said block having varying dimensions to adjust it relatively to the frame; and a bolt extending through the perforations in the saddle and the block.

6. A locomotive saddle having perforations in its sides adapted to receive a pin for retaining a supporting block.

In testimony whereof I have hereunto set my hand.

FRANK M. A'HEARN.
